[57] CLAIM

The ornamental design for a combined pole lamp and planter, as shown and described.

DESCRIPTION

FIG. 1 is a perspective view of a combined pole lamp and planter incorporating my new design;

FIG. 2 is a left side elevational view thereof;

FIG. 3 is a fragmentary front elevational view thereof, the planter being broken away for purposes of disclosure; and

FIG. 4 is a cross section taken along line 4—4 of FIG. 2.

FIG. 1

FIG. 4

FIG. 3
